ABSTRACT: Method and apparatus for distributing strands on a collecting surface aerodynamically. Embodiments of fluid nozzle and air foil members divert the strands after the strands have had a linear velocity imparted thereto to selected deposition points without touching the strands. A sweeping distribution of strands back and forth across a collection surface can be obtained by controlling the flow of fluid through the nozzle, controlling the air pressure between an air foil and a strand, by changing the angle of attack of an air foil, etc.

METHOD AND MEANS FOR STRAND DISTRIBUTION

This application is a continuation of Ser. No. 847,520, filed July 22, 1969, which is a continuation of Ser. No. 530,518, filed Feb. 28, 1966, both now abandoned.

This invention relates generally to method and means for distributing strands and, in particular, to such method and means for the utilization of the concepts set forth herein in accumulating the strand upon a receiving or collecting surface and the making of sheets or mats of fibers in strand form from such accumulation.

Because of the increased general use of fibrous glass mat products, need has arisen for more exacting characteristics and properties for specific applications. Fibrous glass mats have been put to use for such purposes as acoustical, electrical, and thermal insulation as well as for reinforcing and filtering purposes, each such application requiring certain characteristics of strength, porosity and integrity.

One method by which glass fiber formats can be produced is to mechanically attenuate a plurality of glass streams flowing from a feeder or bushing. Attenuation of the streams may be effected by pulling rolls or wheels which draw the streams into fine fibers or filaments as they solidify by reason of exposure to the atmosphere. The solidified filaments are drawn over a size applicator and are then gathered into strand form whereupon the pulling wheels supply the strand for the purpose desired.

Another method of manufacturing glass fibers involves flowing the glass from a feeder as described above and directing a jet of gas thereagainst at high speed to attenuate the streams into fine fibers by disrupting them into varied lengths which collect as a pulpy mass.

Sheet and mat products have been manufactured in the past of both types of glass fibers but strand mats have presented a greater difficulty in manufacture because of their limited ability to form an integral mass. More specifically, the strand has little tendency to intermingle with itself so as to promote formation of an integral mass such as in a mat product. Heretofore, it has been necessary to add agents such as extra quantities of binder material or additional glass fibers of shorter length in order to promote mat integrity. These additions, however, involve additional process steps and corresponding added equipment complexity and cost. In an effort to form a more integral mass, glass fiber strands have been impinged or bounced off of a deflecting surface to provide a fluffy or fuzzy property. That is, an integral glass strand is moved at relatively high speed and directed against a hard surface so that it impinges such surface with a driving force, the product produced being a strand of fuzzy or fluffed character which tends to take on a curl resulting in a generally helical form or swirl. The greater the speed of impingement, the greater the fuzziness created. The fuzziness results from filaments within the strand being dispersed or separated from the main core along at least a portion of their length while the remainder are retained in integrated form. While this method did give a better degree of fine porosity desired for use in acoustical, electrical and thermal insulation the abrading or mechanical handling of the glass strand when deflecting the strand from a surface at a high speed tends to reduce the mechanical strength of the strand or the filaments and is difficult to uniformly deposit over a predetermined area. Further, uniformity of deposition on a collecting surface becomes a problem, which affects integrity of the mat.

In addition to the problem of integrity, other difficulties are experienced with strands in that of themselves they lack the ability to give the degree of fine porosity desired for uses such as acoustical, electrical and thermal insulation. That is, continuous strands by themselves usually fail to provide the multitude of small interstices desired in such insulation materials. Further, in fine mat or thin mat applications where the mat is used as a reinforcing material for such products as roofing materials made from mats impregnated with asphalt, etc., the small interstices are necessary to hold the melted or plastic

filler or impregnator and keep it from running on through the mat when the mat is being combined with the filler to make the final product. Also in this regard, mats made in the past wholly of strand, because of their unusually large interstices, are somewhat rough and fail to provide the fine finish and appearance desired when the glass mats are put to use as reinforcement material in resin laminate structures.

It is particularly desirable to incorporate continuous glass strands in mat products, however, because the mechanically attenuated fibers of which such strands are composed have much greater strength than the blown fibers. Such additional strength incorporated into fibrous mats lends greatly to permitting their use in many installations in which they could not otherwise be used. Both burst and tear strengths of such mats can be made extremely high by reason of the high strength of the fibers or filaments embodied in the strands.

It has been discovered that the proper control of the uniformity of deposition of a strand or of a plurality of strands can provide the characteristics discussed hereinbefore as desirable in the manufacture of strand mats and in other applications as will become apparent. It was further discovered that if a strand has imparted thereto kinetic energy which will provide it with sufficient linear velocity it may be accurately deposited at a predetermined or selected area. Since it is neither desirable nor practical to build production equipment in which various means for imparting kinetic energy to several strands are so disposed as to distribute the strands in different area across a collecting surface, or to obtain overlap of said distributions by mechanically moving the kinetic energy imparting means, a method and means has been devised for imparting kinetic energy and thus linear velocity to a strand and aerodynamic means have been utilized to divert the travel of the strand to allow accurate deposition of the strand at a predetermined or selected point on a collecting surface. There are now available in the prior art several means for imparting kinetic energy to a strand and thus providing the linear velocity desired. The kinetic energy may be imparted, for example, to each segment of the strand by a pulling wheel, pneumatic tube, etc. A strand segment leaves the wheel, tube, etc., at a predetermined velocity which, along with the mass of the segment, determines the kinetic energy imparted to the segment.

45 The strand segments may be made to travel in the same direction from the wheel, tube, etc., so that the velocity given to each segment of strand becomes a linear velocity for the entire strand length after leaving the kinetic energy imparting means.

50 Once the strand (or each segment) is launched with the linear velocity imparted thereto, it begins to lose its linear velocity because of air friction or resistance. As the strand slows, it, in turn, imparts kinetic energy to the air adjacent the strand and, in imparting kinetic energy to the air, and dragging this adjacent air along with it, an air film stream is created surrounding the strand and traveling therewith.

If the original means for imparting kinetic energy to the strand included the production of a carrier air stream already moving adjacent the strand (e.g., use of a pneumatic tube carrying the strand), then the effects of air resistance or friction would be delayed with respect to the strand itself. However, the carrier air stream would act as the previously discussed air film stream in surrounding the strand and traveling therewith.

60 65 After the carrier air stream had lost or began to lose its own "linear velocity" because of friction with ambient air outside the carrier stream, the carrier stream would tend to slow with respect to the strand and the air friction or resistance discussed above between the strand and surrounding air would come into play. Thus, as the carrier air stream slows or disappears, an air film stream would be created from the transfer of kinetic energy from the strand to the slower or immobile air surrounding the strand. In either situation there is an air film stream surrounding and traveling with a strand having a linear velocity.

It is desirable to position a collecting surface for the strand a sufficient distance below the kinetic energy imparting means so that the strand will have used substantially all of the kinetic energy imparted thereto, and thus will arrive at the collecting surface with only enough linear velocity left to deposit the strand firmly on the surface at the desired or predetermined place, without impinging and breaking, abrading or otherwise mechanically weakening or damaging the strands or filaments therein. In the case of foraminous conveyors or collecting surfaces it is desirable to avoid entangling the strand in the foraminous surface. Conversely, it is not desirable for the strand to lose all of its linear velocity too far above the collecting surface, since the strand may "float" or sail through the air and not be deposited at the predetermined point.

Strand deposition or strand segment deposition at a predetermined point is the crux of this invention and is important since uniformity of deposition or the ability to control the uniformity of deposition with all size strands and particularly with "fine" strands (i.e., those made up of much fewer filaments than the ordinary strand which usually includes all of the filaments from a particular feeder and may number from 200 to 400, allows one to control the formation of a mat to provide the multitude of small interstices desired as discussed hereinbefore.

To provide the desired uniformity, it has been discovered that aerodynamic means may be utilized to divert the direction of travel of a strand having a linear velocity, such diversion being accomplished while insuring that the strand has sufficient linear velocity after diversion to reach the predetermined deposition area. To aerodynamically control the deposition or diversion of the strand, a number of approaches are shown hereinafter. First, the air film stream surrounding the strand may be influenced with aerodynamically shaped surfaces. Secondly, a velocity vector differing from the original travel vector of the strand may be applied to the strand and surrounding air film by fluid streams to provide a resultant directional vector which will allow the desired distribution of the strand in an "underdriven" aerodynamic distribution system. Alternatively, fluid streams or jet streams may be utilized to divert the travel of the strand in which the velocity vector added substantially overcomes the initial travel vector and thus provides the uniformity of distribution desired in an "overdriven" type of system. Other aerodynamic diversion approaches not specifically shown, as well as combinations of the approaches shown, may be used.

The various means for strand distribution used in the past are not suitable to obtain the small interstices and fine finish desired. Pulling or attenuating wheels having internal vanes for pushing the strand off the wheel have been mechanically connected in the prior art to vary the pushoff point and thus distribute the strand back and forth across the collecting surface. There is no ability in these arrangements to control the deposition of one strand with respect to the others of a plurality of strands being attenuated by the wheel. Further, the uniformity desired cannot be achieved since substantially true linear velocities cannot be obtained as distinguished from unrelated strand segment velocities.

Various deflecting surfaces have been used for distribution of the strand, including the use of a surface to use the kinetic energy of an impinging strand to fuzz or felt the strand to lower the sizes of the interstices in the mat being formed. The fuzzed or felted strand was distributed over the collecting surface by oscillating the deflecting plate. In another method for distributing the fuzzed or felted strand from the deflecting plate after impingement, a lateral sweeping of the strand from the deflecting member was effected by air blown from pneumatic tubes or nozzles which operated alternately to first deflect the dispersed, fuzzed, or felted strand to one side and then the other side of the collecting surface. While the alternately operating nozzles were effective to distribute the fuzzed strand, they were not able to obtain the uniformity of distribution now required. That is, the linear velocity of the strand has disappeared and has been replaced by strand seg-

ment velocities that are tied together in the random helical configuration of the fuzzed or felted strand resulting from the bounce of the strand from the deflecting plate. The strand cannot then be distributed to a point or the points of deposition with accuracy since the strand no longer has a linear velocity to guide it and a blast from a nozzle at the tumbling segment velocities in the helical configuration is not going to restore linear velocity or straighten the strand for accurate guidance without interfering with the felting at the impingement area. Also, the impingement of the strand on the deflecting surface tends to abrade and mechanically weaken the filaments within the strand.

In view of the foregoing, it is an object of the present invention to provide a novel and economical means for uniformly distributing strands on a collecting surface with great accuracy.

Another object of this invention is to provide a novel and economical method and means for manufacture of strand mats having a high degree of integrity and strength.

A further object of this invention is to provide a novel method and means for manufacture of strand mats having high integrity and strength and a controllable degree of porosity by uniformly distributing fine strands.

A still further object of the invention is to provide a more efficient method and means than existed heretofore for manufacturing mat products in a strand or yarn form.

Still another object of this invention is to provide a method and means for uniformly distributing strands upon a collecting surface with great accuracy solely by aerodynamic influence on the strands.

In attaining the foregoing objectives, it has been discovered as discussed above, that a strand may be guided to a predetermined distribution point by a method and means for utilizing linear velocity in the distribution of the strand. The invention thus features a method for distributing a strand on a collecting surface comprising the steps of imparting kinetic energy to the strand to provide the strand with a predetermined linear velocity and aerodynamically diverting the travel of the strand while insuring a linear velocity of the strand to accurately deposit the strand at a predetermined area on the collecting surface. The method further includes the step of varying the effect of the aerodynamic diversion step to vary the degree or amount of diversion of the travel of said strand and thus the area of deposition. The method includes the distribution of a plurality of strands on a collecting surface which features the steps of imparting kinetic energy to each of the strands to provide each strand with a predetermined linear velocity and aerodynamically diverting the travel of each of the strands while insuring a linear velocity of each of the strands so that again the strand is accurately deposited at a predetermined area.

The aerodynamic diversion step may be accomplished by the use of aerodynamically shaped surfaces to influence the air stream flowing with and surrounding the strand, the use of fluid or jet streams to divert the travel of the strands in an "underdriven" system, and the use of jet or fluid streams to divert the strands in an "overdriven" system, whether a single strand or a plurality of strands are being diverted. The aerodynamic diversion step may also include varying the effect of the diversion to vary the degree or amount of diversion of the strands, up to and including an overlap of deposition of the strands to attain a particular uniformity or pattern desired.

Novel apparatus for accomplishing the above inventive method is disclosed and described in detail for preferred embodiments hereinafter.

Although the principles of the present invention are described as applied in the use of glass strands, the invention is not limited thereto in view of the fact that it has aspects readily applicable to use with strands, yarns and other forms of different materials. For example, the described method of effecting strand distribution can be used for distribution of yarns or slivers as well, or may be used for distribution of strands, yarns or slivers of materials such as cellulose acetate, artificial silk, cotton, wool, or nylon.

Other objects, advantages and features of the invention will become readily apparent when the following description is taken in conjunction with the accompanying drawings, in which:

FIG. 1 is a front elevation of apparatus embodying the teachings of this invention;

FIG. 2 is an enlarged plan view of the apparatus of FIG. 1;

FIG. 3 is a side elevation with portions in section of one of the pull wheels and the motor drive therefore incorporated in the apparatus of FIGS. 1 and 2;

FIG. 4 is a fragmentary front view with parts broken away of the pull wheel and motor drive of FIG. 3 with the assembly turned 90° counterclockwise from the position of FIG. 3;

FIG. 5 is a front elevational view of one embodiment of the fluid nozzle means utilized in this invention;

FIG. 6 is a side elevational view in section of the fluid nozzle means of FIG. 5 taken along lines VI-VI of FIG. 5;

FIG. 7 is a side view of an end plate of the fluid nozzle means of FIG. 6;

FIG. 8 is a side view of a chamber wall of the fluid nozzle means of FIG. 5;

FIG. 9 is a front elevational view of a flow regulating means suitable for use in the fluid nozzle means of FIG. 5;

FIG. 10 is an enlarged view of a portion of a second embodiment of a flow regulating means suitable for use in the fluid nozzle means of FIG. 5;

FIG. 11 is an enlarged view of a portion of a third embodiment of a flow regulating means suitable for use in the fluid nozzle means of FIG. 5;

FIG. 12 is a plot of strand distribution obtained from apparatus illustrated in FIGS. 1 and 2;

FIG. 13 is a fragmentary, somewhat diagrammatic, view in elevation of apparatus illustrating a second embodiment of this invention;

FIG. 14 is a fragmentary, somewhat diagrammatic, view of apparatus illustrating a third embodiment of this invention;

FIG. 15 is a fragmentary, somewhat diagrammatic view of apparatus illustrating a forth embodiment of the teachings of this invention;

FIG. 16 is a fragmentary, somewhat diagrammatic view of apparatus illustrating including foil means having a trailing edge.

FIG. 17 is a partially schematic elevational view of a fifth embodiment of the teachings of this invention; and

FIG. 18 is a view in perspective of an alternative embodiment of aerodynamic diverting means suitable for use in this invention.

Referring to the drawings in more detail, the apparatus of FIGS 1 and 2 includes molten glass feeding bushings 21 and 22 depending from conventional glass melting tanks which are not illustrated. Continuous filaments 23 are drawn from the minute streams of molten glass issuing from orifices of the bushings. It will be considered that a bushing with from 200 to 400 orifices is here utilized, and the filaments are drawn to an average diameter of fifty hundred thousandths of an inch.

Size or a lubricant is applied to the filaments as the latter pass over the traveling belts or aprons of the conventional size applicators 25. The size may be merely water to reduce friction between the filaments as they are subsequently joined together in strand form. A more complex size or binder may be desired to promote coherence of the filaments when combined as strands, and adherence of the strand of filaments to the surfaces of the pulling wheels. Where a mat is to be produced, and the mat is to be ultimately combined with a plastic resin, it may also be desirable to include a coupling agent in the size which facilitates wetting of the mat by the resin.

If the strands are not to be dispersed or reopened later to provide a desired improved porosity, a preferred form of binder is one retaining sufficient cohesive properties when cured to contribute to the bonding of the strand in the mat or other form in which they are collected on the conveyor or the receiving surface. Such a binder has the dual purpose of hold-

ing the filaments together as strands, and bonding the strands into an integrated body.

When mats are produced immediately below the glass filament forming stations, a commonly used lubricant component of the size may be omitted. The inclusion of such a lubricating material has been found necessary for improving the handling ability of the strands where the strands go through subsequent operations such as plying and twisting. Such a lubricant may thus be utilized when the strand is being distributed on a collecting surface or in a container in a predetermined form to be withdrawn from the collecting surface or container at a later date for other uses, such as withdrawing a single strand from a loosely collected mass for later twisting and plying, where the loose accumulation or collection is used as preferred form of packaging rather than winding the strand on a collet or other means.

The filaments from each bushing, after sizing, are grouped together to form a set or group of, in this instance, fourteen strands individually segregated as they travel within fourteen grooves over the respective gathering shoe 27 to second gathering or aligning shoes 31.

From the shoes 31 the two sets of spaced strands 29 and 30 are led around the two idler wheels 33 and, respectively, travel around the pull wheels 35 and 36. These wheels are similarly constructed but are relatively reversed in position and are on opposite sides of the centerline of the receiving conveyor 61.

Motors 37 and 38, respectively, drive pull wheels 35 and 36. The strands carried by pull wheel 35 are released therefrom by the successive projection of fingers of an oscillating spoke wheel through slots in the peripheral surface of the pull wheel 35. Similarly, fingers of another spoked wheel serve this purpose in connection with the pull wheel 36. Both spoked wheels will be shown in greater detail in FIGS. 3 and 4. The strands are kinetically projected in tangential paths from the pull wheel. That is, the rotation of the pull wheels 35, 36 at high speeds imparts a kinetic energy to each segment of the strand as it is pushed off of the wheel. Since the strand segments are all pushed off tangentially in the same direction in this apparatus, the strand segments and thus the entire strand acquires a linear velocity as discussed hereinbefore which is utilized in the uniform distribution of the strands.

The rear side of each pull wheel is covered by an independently mounted, oscillatable backplate on which the associated spoked wheel is carried. Backplate 42 of the assembly including pull wheel 36 may be arcuately oscillated through arm 43. The entire assembly may be positioned on the platform 50 to support the pull wheels 35 and 36 and the equipment associated therewith. Platform 50 may be suspended by angle iron hangers 51. The arm 43 may be arcuately turned to a position to determine the tangential pushoff of the strand from the pull wheel 36. If, as in this instance, it is desired that the tangential pushoff causes the strands to be carried perpendicularly downwardly with their linear velocity,

then the arm 43 may be secured to hanger 51 by a link 52 to retain the strand pushoff at the position desired.

The group of strands 58 thrown down by the pull wheel 35, which has its pushoff point also anchored by a link 52 connected to hanger 51, and the group of strands 59 thrown down by the pull wheel 36 are accumulated, after distribution, in mat form 60 upon the collecting surface, in this case traveling conveyor 61, which may be of carbon steel chain construction.

After the sets of strands 58 and 59 have had imparted thereto kinetic energy and thus provided with a predetermined linear velocity, aerodynamic diversion means, in this instance fluid nozzle means 100, 101, 102, 103 for the sets 58 and 59, respectively, distribute the strands across the width of the collecting surface 61.

The pull wheel 35 and the drive therefore are shown in more detail in FIGS. 3 and 4. On the shaft of motor 37 is a toothed pulley 64 which has driving connection through the segmented timing belt 65 with toothed pulley 66. The latter is mounted on the outer end of shaft 67, on the other end of which is carried the pull wheel 35.

70
75

The shaft 67 is journaled in the stationary casing 69 upon which the motor 37 is supported. The pull wheel is held upon the threaded stud 71 of the shaft 67 by the barrel nut 72. The hub 73 of the pull wheel has a bored section fitting over the smooth portion of the stud 71 and held against a shoulder terminating the smooth portion by the barrel nut 72. The main body of the pull wheel is fastened to the hub 73 by machine screws 75 and 76. A cap 78 covers the outer end of the bore through the hub.

In a preferred embodiment, the pull wheel 35 may be 12 inches in diameter and has a series of peripheral cross slots 81, approximately $1\frac{1}{8}$ inches long, three-sixteenths of an inch wide, and spaced five-sixteenths of an inch apart. To reduce the wear, the strand receiving surface of the pull wheel is given a hard surface such as an electrolytic deposit of aluminum oxide or a coating of nickel phosphate.

The fingers 83 of the spoked wheel 39 within the pull wheel 35 are dimensioned and motivated to successively project through the slots 81. The spoke wheel is mounted on shaft 87 projecting from the backplate 41 and carries the toothed pulley 89 on a rearward extension of the wheel hub 73.

The main body of the spoke wheel 39 is in this instance about $3\frac{1}{4}$ inches in diameter with the fingers 83, 27 in number, radially extending slightly more than thirteen-sixteenths of an inch from the periphery of the main body. The exterior portions of the fingers are generally of rectangular blade from 1 inch wide with a thickness of 0.024 of an inch. About one-eighth of an inch of the outer end of the fingers extends out of the pull wheel slots at the point of their greatest projection.

The movement of the fingers 83 into the slots 81 and their momentary projection through the slots to release the strands is synchronized through the timing drive between the pull wheel and the spoke wheel. This includes the toothed pulley 91 fixed upon the hub 73 of the pull wheel, the cog timing belt 93 running over the pulley 91, and the pulley 89 on the shaft 87 upon which the spoke wheel is journaled.

The back plate 41, oscillatable as described hereinbefore through yoke 57 to which it is attached, is mounted through bearings on the stationary casing 69. Yoke 57 and therethrough backplate 41 and the spoke wheel 39 are oscillated to a position where it is desired to push the strands off in tangential direction, in this instance, perpendicularly downwardly toward the collecting surface 61. These adjustments provide the degrees of tolerance necessary to set up the kinetic energy imparting means in conjunction with the installation of the aerodynamic diverting means to uniformly distribute the strand accurately to predetermined areas on the collecting surface 61.

Air movement into the interior of the pull wheel 35 is curtailed by the shroud ring 85 held to the inner edge of the wheel periphery by a series of machine screws. A baffle 95 intermittently cylindrical in form, is carried by the oscillating backplate 41 and lies under the slots 81 except for an open section of the baffle in the region of the spoke wheel. This prevents air movement outwardly through the slots which is apt to irregularly release the strands from the pull wheel and interfere with the initial direction of travel desired and provided by the imparting of the kinetic energy and the resultant linear velocity of the strand.

With the high-peripheral speed of the pull wheel, the strands are forcefully projected in straight tangential lines from the point of disengagement effected by the fingers of the spoke wheel. The kinetic energy that the strands thus acquire carries them in straight courses to the region of application of aerodynamic diversion to acquire a new line of travel to the desired point on the collecting surface.

Referring to FIGS. 5 through 8 there is shown in greater detail the construction of a suitable aerodynamic means for diverting the travel of the strands to a desired distribution point or area. The first embodiment of the aerodynamic means as shown in the FIGS. 5 to 9 comprises a fluid nozzle means adapted to discharge a regulated fluid stream to divert the travel of a plurality of strands and the air film streams surrounding and traveling with the strands.

The fluid nozzle means comprises a plenum chamber enclosed on the sides by plenum chamber walls 110, 111 and 114, with end plates 112 and 113 completing the enclosure. A suitable fluid supply, preferably gas or air but may be a liquid fluid, may be connected to the interior of the chambers via ports 118, 119 formed in the end plates. The side chamber walls 110 and 111 are secured together in a configuration resembling in section a truncated apex of a triangle. The forward or nozzle end 120 of the chamber wall 110 may be formed with a substantially flat abutting surface 109. Similarly, the forward or nozzle end 121 of the chamber wall 111 may also be formed with a substantially flat abutting surface 108 to mate with surface 109. An elongated slot 122 is formed in the abutting surface 108 of the nozzle end 121 of the sidewall 111 so that when the forward or nozzle ends 121, 120 of the sidewalls 111, 110 are brought together at abutting surfaces 108, 109 an elongated nozzle opening 122 is formed.

In order to provide for the shaping of the stream issuing from the elongated nozzle opening 122, or to divide the stream issuing from elongated nozzle opening 122 a plurality of vanes 117 may be distributed along the opening 122 at spaced intervals. The vanes 117 may be formed separately or may be milled in place from the chamber wall 111 at the time of making the elongated slot 122 in the abutting surface 108 of the forward end 121. In order to support the vanes 117, receiving slots for the vanes 117 may be formed in the abutting surface 109.

The elongated nozzle opening 122 communicates with the plenum chamber formed by the sidewalls 110, 111, 114 and the end plates 112, 113. To smooth the turbulence of the fluid as it proceeds from the plenum chamber to the elongated nozzle opening, a screen 115 (FIG. 6) may be disposed between the plenum chamber and the nozzle opening 122. The screen may be held in place by suitable means such as the receiving slots 105, 106 shown formed in the opposing sidewalls 110, 111 (see FIG. 6).

A flow regulating means 130 may be placed between the plenum chamber and the elongated nozzle opening 122. The regulating means 130 may be held in place by any suitable means. Slots 131, 132 formed in the opposing interior surfaces of the sidewalls 110, 111, respectively, provide means for removably securing the regulating plate means 130 in the desired position. If a change in the regulating plate means 130 is desired, it may be effected by removal of the plate 130 through the port 133 (FIG. 7) formed in end wall 112. A plug may be screwed into port 133 to secure the plate 130 in position.

Referring to FIGS. 9, 10 and 11 there are shown three embodiments of the regulating means suitable for use in this invention. In FIG. 9 the regulating means 130a is shown as having an orifice means 135a formed in the plate, which orifice means gradually increases in size from the left to the right side of the plate 130a. This regulates and distributes the flow of the fluid out through the elongated nozzle opening 122 in a form designed to apply more aerodynamic deflection of the strands positioned opposite the larger opening of the orifice plate than the corresponding push applied to a strand positioned opposite the narrower opening in the plate.

In FIG. 10 the second embodiment 130b is shown in which a gradual increase in orifice size is not utilized, but instead a succession of orifice slots 136, 136a, 136b, etc., are formed adjacent to each other, and preferably connecting, across the length of the plate. This too regulates the flow of the air but tends to produce a series of successively larger flat jets or streams across the width of the nozzle opening. Again, more aerodynamic push is effected against a strand opposite a larger opening than a strand opposite a smaller opening.

In FIG. 11 a regulating means 130c is shown in which has been formed a row of successively larger perforations or orifices 137, 137a, 137b, 137c, etc. The effects upon the strands opposite these openings is the same as described hereinbefore, however, the individual orifice openings tend to more directly confine a fluid or jet stream to action in an individual area. The use of any of the orifice or flow regulating plates shown

hereinbefore is determined by the application and results desired.

In the apparatus shown in FIG. 1, opposing aerodynamic means 100, 101 and 102, 103 are used for distribution. That is, a fluid nozzle means is disposed on each side of the plane defined by the set of strands 58 or 59 leaving the pull wheels 35, 36. To obtain the results desired in this particular instance the nozzle openings are aligned horizontally, but displaced laterally, as noted in the plot of aerodynamic effect upon the strands in FIG. 12. The group of strands 1 through 14 as shown in section in solid lines in FIG. 12 are in the plane at the zero deflection and zero pressure differential line on leaving the pull wheel 35. The nozzles may be laterally displaced as noted hereinbefore and each provides aerodynamic pressure effects as noted by the solid line curves 138a and 138b when operative singly. When both are operative at the same time, a pressure differential or addition occurs where the curves 138a and 138b overlap and is noted by the dotted line 138c.

In the experiment conducted for the results shown in the plot FIG. 12, each nozzle was provided with approximately 10 p.s.i. of air pressure. The plus and minus figures on the left of the graph indicate the velocity differential in pressure that results from the two nozzles pointing toward each other. The velocity difference working upon each strand would then divert the strand from the zero line to the point shown by the strands noted in new positions by dotted lines to obtain the pattern desired. The aerodynamic pressure exerted upon the strand and upon the air film carrier stream around the strand is sufficient to divert the travel of the strand to the degree desired without causing the strand to lose the linear velocity imparted thereto by the pull wheels 35 and 36. The strand thus diverted retains linear velocity and the travel direction imparted to it by the aerodynamic diversion means and reaches the predetermined point desired for its deposition on the collection surface. Each strand retains its line of travel more accurately than any method known before in the prior art, allowing greater uniformity of deposition and thus uniformity of mats or other products formed from the method and means of strand distribution shown herein.

While the plot of strand distribution shown in FIG. 12 is a steady state operation resulting from steady fluid pressure in both nozzles, it is to be noted that the fluid pressures for each nozzle may be changed to vary the effect of aerodynamic diversion and thus the distribution of the strands. That is, the fluid pressures of one or both of the nozzles may be changed to obtain a sweeping distribution and, if desired, an overlap of distribution of one or more adjacent strands. This may be accomplished by use of electrically controlled valves placed in the fluid supply lines, as noted in FIG. 2. An air supply line 16 may be connected to opposing nozzle means via control valves 17 and 18. The control may be gradual or, as shown, a switching means 19 may be used to regulate the valves to deliver, for example, between 7 and 10 p.s.i., alternately, thus modulating and causing a sweeping distribution.

In FIG. 13 a different type of strand disengagement means is illustrated. A high-speed rotary pulling wheel 141 is mounted upon a generally horizontal drive shaft 142 and rotated at high speed to produce a peripheral speed in the order of 15,000 feet per minute or more. Although this arrangement may be used with a plurality of strands, only one strand is shown for purposes of clarity. A strand 143 is guided into engagement with the periphery of the wheel 141 by means of a guide wheel 140. The pulling wheel 141 may have an uninterrupted, smooth periphery. Since very high-peripheral speeds may be desired in order to impart a predetermined kinetic energy and thus a predetermined linear velocity to the strand, the wheel must be formed from material having high-tensile strength and preferably a material which can be polished to have a very smooth surface. While all of the forces employed in attenuating the strand on a single wheel are not understood, apparently properties of the liquid on the wheel such as surface tension, viscosity, lubricity and cohesion cause the strand to adhere to the wheel. In addition, there is apparently present,

at least to some extent, a force generally known as the "belt effect" tending to squeeze the strand radially inwardly against the periphery of the wheel as the strand wraps around the wheel. In any event, by thus guiding the strand 143 into contact with the surface of the wheel 141 and carrying the strand around the periphery of the wheel 141 for a considerable distance, say somewhere in the order of 120° to 300° or thereabouts, sufficient tractive force is applied to the strand 143 to attenuate its individual filaments and to pull them over a gathering shoe and the aligning wheel 140.

Having thus engaged the strand with the periphery of the pulling wheel 141, it becomes necessary and difficult to effect disengagement of the strand therefrom if not using the pushoff method shown hereinbefore. The tractive force, whether considered to be surface tension or belt effect or other, tends to hold the strand against the periphery of the wheel and, unless in some way interrupted, the strand will continue to wrap onto the surface of the wheel piling up in a "lap up" or "lick." Means have been shown before in prior art for effecting disengagement of the strand 143 from the surface of the pulling wheel 141, which means are interposed adjacent to, but not in contact with, the periphery of the pulling wheel 141 for interrupting or deflecting at least a part of the film of air which rotates with the strand and the pulling wheel 141. The presence of such interrupters apparently causes an aerodynamic "bubble" or deflection which enters in between the strand 143 and the surface of the wheel 141, "peeling" the strand 143 off the wheel 141.

In FIG. 13 this strand disengagement effecting means as illustrated as an air foil 145. In this case it is believed that an area of high-pressure builds up at the leading edge of the air foil 145 and an area of lower pressure is created over the back surface of the air foil. The first high-pressure area effects disengagement of the strand 143 from the wheel 141 and the second, or low-pressure area bends the strand back to a path, in the case of the prior art, generally parallel to a tangent to the pulling wheel 141 at the point of departure of the strand therefrom. In this invention the trailing edge of the air foil is aerodynamically shaped to distribute the strand to a predetermined point on a collecting surface. The pulling wheel is rotated with sufficient speed so that the linear velocity imparted to the strand by the kinetic energy received from the wheel is sufficient after diversion by the trailing edge of the air foil to accurately reach a predetermined deposition point. Thus the strand is deposited at a point determined by the shape of the trailing edge of the air foil 145 very accurately and uniformly.

In order to vary the effect of the aerodynamic distribution means, the pressure on the side of the air foil adjacent the strand 143 may be varied. This may be effected by providing a fluid stream or nozzle means 150 communicating with the air foil surface adjacent the strand. The nozzle 150 may communicate with a fluid stream supply 153 via a variable delivery pump 152. The action of the pump 152 may be controlled by a suitable electrical or mechanical control means 154. If a sweep of the strand is desired across the collecting surface, the pressure may be increased and decreased at the adjacent surface of the air foil 145 by increasing and decreasing the supply of fluid to the nozzle 150. That is, with no control input the air film stream surrounding and traveling with the strand will tend to attach to the adjacent surface of the air foil. Control input to nozzle means 150 will separate the air film stream from the air foil and thus change the degree of diversion of the strand.

Referring to FIG. 14, there is shown an embodiment of the invention utilizing the principles set forth in the apparatus illustrated in FIG. 13 but in which a second air foil means 145a has been added, with a similar nozzle opening 150a, supply line 151a, variable pump 152a, a supply source 153a, and control 154a. By using a second similarly shaped air foil means 145a, a bistable action may be effected and more uniformly control the sweeping distribution of the strand 143. That is, as pressure is increased on the adjacent surface of the air foil 145, the strand 143 moves away from air foil 145 and ap-

proaches air foil 145a. At some point in the movement away from the air foil 145, the attraction toward the surface of the air foil 145a overcomes that of the attraction of the surface of the air foil 145 causing the surrounding air film stream and the strand to move over adjacent to the air foil 145a. Since this may be made a bistable action, the strand 143 will remain adjacent to foil 145a until the air pressure on its strand adjacent surface is increased via nozzle 150a to move the strand back across. Although normally the arrangement illustrated in FIG. 14 may be used as a bistable arrangement with the strand being swept continuously back and forth between the surfaces of the air foils 145 and 145a, it will be noted that many patterns may be formed by varying the pressures at the nozzles 150 and 150a at selected times to provide movement or distribution less than the full sweep of the strand 143 between its two stable positions.

Referring to FIG. 15, there is shown an arrangement for feeding a plurality of strands between the coacting peripheries of high-speed rotary pulling wheels so that the strand is tightly gripped between the surfaces of the wheels and linearly fed by the wheels to the aerodynamic diversion means. The coacting pulling wheels usually have resilient or deformable surfaces so that they can be squeezed tightly together around the strand being fed. This limits the speeds with which such wheels can be rotated because resilient materials cannot withstand extremely high-centrifugal forces and, unless the size of the wheels is so large as to be cumbersome, maximum linear speeds in the order of 14,000 to 15,000 feet per minute cannot be exceeded without damage to the wheels themselves. However, in some instances, it is desirable to be able to use coacting pulling wheels in the manufacture of strands and/or strand mats.

In FIG. 15, a group of strands 162 is pulled or attenuated by coacting pulling wheels 160, 161. An air foil means 170 is situated beneath the wheels 160, 161 and disposed adjacent to the air film streams surrounding the strands and the strands themselves. As in the previous apparatus illustrated in FIGS. 13 and 14, the air foil means 170 has a trailing edge 171 aerodynamically shaped to effect distribution of a particular strand to a particular point. As will be noted in FIG. 15, the trailing edge 171 of the air foil 170 is given a warped or curved form so that a strand 162a will be influenced by the aerodynamically shaped surface of the foil 170 to arrive at a different point or area of distribution than an adjacent strand 162b, which is under the effect of a slightly differently shaped trailing portion of the trailing edge 171. Similarly, strands 162c, 162d, may be distributed at different areas depending upon the configuration of the trailing edge and general configuration of the air foil means 170. In order to effect a sweeping action, a plurality of nozzle means 172 may be provided on the strand adjacent surface of the air foil means 170 to increase or decrease the pressure on the strand adjacent surface of the foil 170 thus either moving the final distribution point of the strand or strands, or allowing for a sweeping action of one or all of the strands in the group of strands 162.

In FIG. 16 there is shown a pulling wheel 180 for attenuating a strand 181 and/or imparting kinetic energy thereto. An air foil means 182 is shown and may be used as illustrated in FIGS. 13 and 14 to disengage the strand from wheel 180 in addition to aerodynamically diverting the direction of travel of the strand 181. In either instance, the air foil 182 is provided with lever support means 183 for mechanically varying the effect of the aerodynamic diverting means. That is, with the air foil 182 and the lever 183 in the position shown in the solid lines, the strand 181 will be diverted to the collecting surface in the direction noted by the strand position drawn in solid lines. However, the effect may be changed through the variation of the angle of attack of the aerodynamic diverting means, shown here as foil means 182, so that if the air foil is given the new position shown in the dotted lines the trailing edge 185 of the air foil is moved to a new position and thus the direction of travel of the strand 181 is aerodynamically diverted and will follow the course dictated by the position of the trailing edge and the general configuration of air foil 185.

It is to be noted that although embodiments have been shown with particular combinations of strand disengagement and/or aerodynamic diverting means, other combinations of these means may be effected to attain desired results even though the particular combinations are not shown in the drawings. For example, air pressure increasing and decreasing means may or may not be used with any or all of the configurations shown herein. Means for changing the angle of attack of the air foil means may be utilized with the configurations shown in FIGS. 13, 14, 15 and 17 in addition to or instead of the air pressure varying means. Equivalents of the particular components shown may be substituted to obtain the novel concept disclosed herein.

Referring to FIG. 17, there is shown a still further embodiment of the invention in which pulling wheel means for attenuating filaments or imparting kinetic energy to a strand are replaced by a pneumatic tube 190 which draws the strand 191 through an eye 192 from a strand package 193. The strand driving air is introduced at the side of the path of travel taken by the strand 191 and carries the strand with it through the tube to impart velocity thereto sufficient to add kinetic energy to the strand and to provide the strand with the desired linear velocity. In combination with this alternative kinetic energy imparting means there is shown in section an aerodynamic diverting means 200 which has a three dimensional trailing edge for diverting the strand and may surround the strand completely. The air foil means 200 operates upon the principles discussed hereinbefore and the travel of the strand is influenced by the aerodynamic configuration of the air foil surface and trailing edge 201 of the air foil means. One or a plurality of nozzles 202 may be formed on the interior surface of the air foil means 200 and be connected to various fluid supplies and/or fluid pressure variation means as shown hereinbefore. The combination of the aerodynamic shape of the trailing edges 201 of the air foil means 200 and the increase or decrease of pressures through the nozzles 202 may be used to obtain steady state distribution of the strand at a desired point, to obtain a lateral sweeping of the strand 191 back and forth much in the manner described for the bistable mechanism illustrated in FIG. 14, or may be used to obtain other patterns of distribution as desired depending upon the variation of the pressures produced by the nozzles 202. The other variations may include the description of a circle by the travel of the strand upon a collecting surface or in a container package, the description of a figure eight on the collecting surface or in a container package, or other patterns as desired.

Referring to FIG. 18, there is shown a nozzle similar in most ways to the construction of the nozzle illustrated in FIGS. 5 through 8. However, the nozzle 210 in FIG. 18 differs in providing an elongated nozzle opening 211 which is curved or warped so that the effect is to provide a different angle or degree of attack by the fluid stream or streams upon each of the individual strands passing in a parallel plane in front of the elongated nozzle opening 211. Vanes 212 may be used to individualize jet streams emerging from the elongated nozzle opening 211 or to straighten or shape the general flow from the nozzle opening. Regulating means similar to that shown hereinbefore having various shaped orifices may also be used in the nozzle 210.

The nozzle means 210 is most applicable to situations in which only a single nozzle is used and it is desired to supply a fluid stream or a jet stream at a velocity which is sufficient to overcome substantially all of the vectorial velocity imparted by the kinetic energy from the kinetic energy imparting means. In other words, the kinetic energy imparting means is used primarily in this instance to deliver each individual strand to a desired position in front of a predetermined portion of the elongated nozzle opening 211. The pressure from the jet or fluid streams from the nozzle 210 is sufficient to drive, entrain or substantially overcome the kinetic energy vector imparted to the strand earlier to drive the strand to a predetermined deposition point. The imparting of a linear velocity from the aerodynamic diverting means itself is attained in this configuration and is as important as in the previous configurations to

insure that the strand is deposited with great accuracy at the predetermined area as desired.

Sweeping action of deposition may be attained here by varying the fluid pressure as in the previous models shown herein. Since the final direction of travel of the strand is substantially the same as the vector given to it by the jet or fluid stream from the elongated nozzle opening 211, the distribution system of this type is called an "overdriven" system. The nozzle of FIG. 18 may also be used in an "underdriven" system where the velocity vector from the kinetic energy imparting means has a substantial effect upon the resultant vector, and may be used for its value in having the nozzle pointing at the strands from different angles to vary the effect of the jet streams via the angle of attack, as well as by pulsing or modulating the supply of the jet stream to the nozzle 210.

There has thus been described and disclosed herein a method and means for strand distribution which enables more accurate and uniform distribution than any method heretofore known. In the more specific application of continuous mat forming directly from fiber forming stations the invention allows excellent mat forming without packaging which cuts costs and breakdowns. The strand is not mechanically handled, therefore, strength remains high. This invention allows the making of strand products with "fine" strands, i.e., those with few filaments as opposed to coarse strands, that cannot stand up under normal packaging techniques. By being able to make strand products from very "fine" strands it approaches making products with individual filaments, thereby improving the porosity of the product, reducing interstices thus providing better insulation and improving strength in reinforcing applications.

Possible modifications and substitution of elements of the apparatus of this invention will easily occur to those skilled in the art, and such obvious changes are considered within the spirit and scope of this invention.

We claim:

1. Apparatus for uniformly distributing a strand on a collecting surface comprising a moving collecting surface, means for delivering a strand along a linear path to a diversion station including means for imparting kinetic energy to said strand to provide said strand with a linear velocity toward said collecting surface sufficient to carry the strand to a selected deposition point after passing a diversion station, said strand with said linear velocity having an air film stream surrounding and traveling with said strand, said diversion station including aerodynamic means positioned adjacent but not touching said strand and adjacent said air film stream for diverting the travel of said strand and said surrounding air film stream to said selected strand deposition point on said collecting surface without mechanical impingement, said aerodynamic means having an air foil surface means adjacent said air film stream with a trailing edge shaped to influence the direction of flow of said air film stream to change the direction of travel of the strand in said air film stream to said selected deposition point on said moving collecting surface to attain a predetermined uniform deposition of said strand on said moving collecting surface.

2. Apparatus as defined in claim 1 which further includes control means comprising means for varying the air pressure on the surface of said air foil surface means adjacent said air film stream.

3. Apparatus as defined in claim 2 in which said air pressure varying means comprises a fluid nozzle means communicating with said adjacent surface of said air foil means.

4. Apparatus as defined in claim 3 which further includes means for supplying a fluid to said nozzle and means for controllably varying the amount of fluid supplied to said nozzle.

5. Apparatus as defined in claim 1 which further includes control means comprising means for varying the relative angle of attack between said air foil surface means and said adjacent air film stream.

6. Apparatus as defined in claim 1 in which said aerodynamic means comprises a pair of air foil surface means positioned

adjacent to and on opposing sides of said strand and said air film stream.

7. Apparatus as defined in claim 6 which further includes control means comprising means for varying the air pressure on the air film stream adjacent surface of each of said air foil surface means.

8. Apparatus as defined in claim 7 which further includes means for increasing the air pressure on an air film stream adjacent surface of one air foil surface means to cause said strand and said air film stream to move to and stay in an air flow juxtaposition with an air film stream adjacent side of said other air foil surface means, said strand and surrounding air stream staying in the latter position even though said air pressure increase on the air film stream adjacent side of said one air foil surface means is removed.

9. Apparatus as defined in claim 7 in which said control means includes means for alternately varying the air pressure on said air film stream adjacent surfaces of said air foil surface means to cause said strand and said air film stream to move back and forth between said air film stream adjacent surfaces thereby distributing said strand on said moving collecting surface in a controlled sweeping action.

10. Apparatus as defined in claim 1 in which said air foil surface means comprises an air foil member surrounding said strand and said air film stream and has an aerodynamically formed interior surface with a trailing edge shaped to divert the travel of said strand and said air film stream.

11. Apparatus as defined in claim 10 which further includes a plurality of fluid nozzle means communicating with said interior aerodynamic surface of said air foil surface means for selectively varying the air pressure on said aerodynamic surface.

12. Apparatus for uniformly distributing a plurality of glass fiber strands on a collecting surface in a uniform matlike mass comprising a moving collecting surface, means for delivering each strand along a linear path to a diversion station including means for imparting kinetic energy to each of said plurality of strands to provide each of said plurality of strands with a linear velocity in spaced and substantially parallel relationship with respect to each other, the linear velocity of each strand being sufficient to carry each strand to a selected deposition point on said collecting surface after passing said diversion station, each of said strands having an air film stream surrounding and traveling with said strand, said diversion station including air foil surface means positioned adjacent but not touching a plane defined by said substantially parallel strands for diverting the travel of said strands without mechanical impingement through reaction between said air film streams and an aerodynamically shaped strand adjacent surface formed on said air foil means and having a trailing edge influencing the direction of travel of said air film streams and the strands therein to selected deposition points on said collecting surface.

13. Apparatus as defined in claim 12 which further includes control means for selectively varying air pressure on the aerodynamic surface of said air foil means adjacent said plurality of strands and their surrounding air film streams to vary the degree of diversion of travel of said strands.

14. Apparatus as defined in claim 12 in which said trailing edge portion of said aerodynamic surface is shaped to vary the angle of attack and thus the amount of reaction between each of said air film streams of each of said plurality of strands and said air foil means, thereby depositing each of said strands at a different selected deposition area on said collecting surface.

15. Apparatus for uniformly distributing a plurality of glass fiber strands in a uniform matlike mass on a collecting surface comprising a moving collecting surface, means for delivering each strand along a linear path past a diverting station including means for imparting kinetic energy to each of said plurality of strands to provide each of said plurality of strands with a linear velocity toward said collecting surface in spaced relationship with said other strands, the linear velocity of each strand being sufficient to carry each strand to a selected

deposition point on said collecting surface after passing said diverting station, said diverting station including fluid nozzle means between said kinetic energy imparting means and said collecting surface for projecting strand diverting streams at said plurality of strands to divert the path of travel of each strand in cooperation with the linear velocity thereof and without mechanical impingement to a selected deposition point on said collecting surface.

16. Apparatus as defined in claim 15 which further includes control means for modulating the flow of fluid to said nozzle means, thereby modulating the amount of diversion of the paths of travel of said strands.

17. Apparatus as defined in claim 15 in which said fluid nozzle means comprises a plenum chamber and a plurality of stream shaping jet means communicating with said chamber.

18. Apparatus as defined in claim 17 in which said fluid nozzle means further includes a screen means positioned between said plenum and said jet to smooth turbulence in said fluid.

19. Apparatus as defined in claim 17 in which said fluid nozzle means further includes means for regulating the flow of fluid between said plenum and said jet means.

20. Apparatus as defined in claim 19 in which said regulating means comprises removably securable plate means having flow controlling orifice means formed therein.

21. Apparatus as defined in claim 17 in which said stream shaping jet means includes a plurality of vanes for directing the flow of fluid.

22. Apparatus as defined in claim 15 in which said fluid nozzle means comprises means for projecting a plurality of diverting streams at different angles with respect to a plane defined by a plurality of substantially parallel strands to provide differing amounts of diversion for each of said plurality of strands.

23. Apparatus for uniformly distributing a plurality of glass fiber strands on a collecting surface comprising a moving collecting surface, means for delivering each strand along a linear path to a diversion station including means for imparting kinetic energy to each of said plurality of strands to provide each of said plurality of strands with a linear velocity toward said collecting surface in spaced and substantially parallel relationship, the linear velocity imparted to each strand being sufficient to carry each strand to a selected deposition area after passing said diversion station, said diversion station including a pair of fluid nozzle means positioned on opposite sides of a plane defined by said parallel strands for projecting fluid streams to divert the path of travel of each of said strands in cooperation with the linear velocity thereof and without mechanical impingement so that each said strand has linear

velocity after said diversion to carry it accurately in the diverted direction to said selected deposition area on said collecting surface.

24. Apparatus as defined in claim 23 which further includes means for controlling the flow from said pair of fluid nozzle means to control the amount of diversion of said strands.

25. Apparatus as defined in claim 23 in which each of said pair of fluid nozzle means defines a substantially planar area by projecting a plurality of substantially parallel streams at

10 said plurality of strands.

26. Apparatus as defined in claim 25 in which said pair of fluid nozzle means are aligned on opposite sides of said strands so that at least part of said streams projected by each of said nozzles meet to provide a resultant force to apply to at least 15 part of said strands to obtain the amount of diversion desired.

27. Apparatus as defined in claim 23 which further includes means for controlling the flow of said streams from one of said nozzle means.

28. Apparatus as defined in claim 23 which further includes means for selectively varying the flow of said streams from each of said nozzle means.

29. Apparatus as defined in claim 23 in which each of said nozzle means comprises a plenum chamber having an elongated nozzle opening and means for regulating the flow along 20 the length of said elongated nozzle opening.

30. Apparatus as defined in claim 29 in which said regulating means comprises a plate having graduated orifice means formed therein.

31. A method for uniformly distributing a plurality of strands in a matlike array on a collecting surface comprising the steps of delivering each of said strands along a linear path to a diversion point while imparting kinetic energy to each of said strands to provide each of said strands with a preselected linear velocity past said diversion point toward said collecting surface, and applying aerodynamic forces to said strands for diverting the travel of each individual strand with respect to the remainder of the strands at said diversion point solely by aerodynamic pressure influence on said strands and without mechanical impingement diversion to deposit said plurality of strands at a like plurality of different selected areas on said collecting surface.

32. A method as defined in claim 31 which further includes the step of increasing and decreasing the amount of said aerodynamic pressure force diversion on said strands to obtain 40 a sweeping distribution of said strands on said collecting surface.
